UNITED STATES PATENT OFFICE.

CHARLES C. MITCHEL, OF LYNDHURST, NEW JERSEY.

REAMER.

1,062,841.

Specification of Letters Patent.

Patented May 27, 1913.

Application filed September 6, 1912. Serial No. 718,856.

To all whom it may concern:

Be it known that I, CHARLES C. MITCHEL, a citizen of the United States, residing at Lyndhurst, in the county of Bergen and 5 State of New Jersey, have invented a certain new and useful Improvement in Reamers, of which the following is a specification.

The invention relates to reamers of the 10 expanding type, and is designed more especially for service in deep-well drilling.

In drilling hard rock the drill gradually diminishes exteriorly by wear and it is sometimes necessary to ream the bore to 15 permit the well-casing to be driven, and frequently in drilling through hard rock into a pocket or stratum of soft material, as sand, the drill in breaking through the lower portion of the rock leaves an irregular opening 20 which must be shaped cylindrically to receive the casing. The improved reamer is intended for such service, and the object of the invention is to provide a strong, simply constructed tool of this character which may 25 be easily introduced in the bore, lowered to the required depth, and expanded positively at the point to be reamed, and easily and positively collapsed for withdrawal.

The invention consists in certain novel 30 features of construction and arrangement by which the above objects are attained, to be hereinafter described.

The accompanying drawings form a part of this specification and show an approved 35 form of the invention.

Figure 1 is a vertical central section through the improved reamer, in the expanded condition, partly in elevation, and Fig. 2 is a similar view showing the reamer 40 collapsed. Fig. 3 is a face view of the bottom of the reamer. Fig. 4 is a transverse section, taken on the line 4-4 in Fig. 1, and Fig. 5 is a corresponding section on the line 45 5-5 in Fig. 2. Fig. 6 is a side view of one of the cutters. Fig. 7 is a face view of the exterior of the same, and Fig. 8 is a corresponding top view.

Similar letters of reference indicate the same parts in all the figures.

50 A is the spindle-box comprising a hollow cylindrical body having a solid head A¹ drilled and tapped to receive the screw-threaded spindle B on the lower end of a shank B¹, and having the lower interior face 55 of the head A¹ adapted to serve as a shoulder A² or abutment for an adjustable collar

C on the spindle. On the lower end of the spindle-box is secured the tubular cutter-box D having a series of vertical slots d and closed at the lower end by a plate D¹. 60 Within the cutter-box are the cutter-bars E¹ arranged segmentally about the axial line of the box and each having a blade or cutter E engaged in one of the slots. The inner faces of the cutter-bars are curved and also inclined downwardly to match to the surface of a long cone F secured to the lower end of the spindle B and raised and lowered in the cutter-box by the advance and re-cession of the spindle due to the rotation of 70 the latter in the screw-threaded head A¹ by turning the shank B¹.

In introducing the reamer into the bore, the shank is turned and the cone thus raised until the collar C strikes the shoulder A², 75 thus partially withdrawing the cone from the cutter box and permitting the cutter-bars to move inwardly sufficiently to bring the blades within the circumference of the cutter-box while maintaining engagement 80 with the slots. In this condition, shown in Fig. 2, the tool is lowered to the required depth in the well-bore, and the shank then turned to force the cone downwardly in the cutter-box and the cutters radially outward 85 through the slots therein. By continuing the rotation of the shank the cone is forced into sufficiently strong frictional contact with the cutter-bars to cause the cutter-box to partake in the rotation and turn with 90 the shank and spindle, with the cutting blade of each cutter-bar projected fully through its slot, as in Fig. 1, and acting upon the interior of the well-bore. A reversal of rotation raises the cone, releases 95 the cutter bars and their box and permits them to assume the collapsed position ready for withdrawal from the well.

The cutter-box is attached to the spindle-box by screw-threads at a thus permitting 100 the cutter-box to be removed and the substitution of another of larger diameter, to be operated by the same or another cone, as will be understood.

A central opening d¹ in the plate D¹ permits material in the cutter-box to escape, and is preferably large enough to permit the lower end of the cone to pass in case the cone should be forced downwardly far enough to strike the plate and thus arrest its movement, and holes d² d² are provided to receive pins on a suitable wrench, not shown, by

which the plate may be removed and replaced in assembling the parts.

The collar C is threaded to match the spindle and may be adjusted thereon to limit the rise of the cone and thus determine the amount of inward movement permitted to the cutters relatively to their inclosing cutter-box. Set screws C¹ are provided to insure the position of the collar, and a pin 10 G extending transversely through the lower end of the spindle and the screw-threaded extension F¹ of the cone F prevents accidental separation at this point in the operation of retracting the cone.

15 The cutter-bars are segmental in cross-section, having their outer faces E² on which the narrow blades or cutters E are carried, curved to match to the interior of the cylindrical cutter-box, and their inner faces E² 20 curved and tapered to match to the surface of the cone when the latter is fully down and the outer faces E² in firm contact with the interior of the cutter-box, thus insuring solidity during the reaming operation with 25 strong frictional contact between the cone and bars. The edges of the blades are preferably inclined downwardly so their radial projection is slightly greater at the upper portion to permit the reaming to be performed gradually as the tool is fed downward in the bore.

It will be noted that the cone is always in engagement with the cutter-bars sufficiently to hold them in place with their blades engaged each in its respective slot, and prevent the inward escape or displacement of each.

Modifications may be made within the scope of the claims, in the forms and proportions of the parts. A greater or less 40 number of cutters may be employed, and the shape of the blades may be changed as the character of the work may dictate.

I claim:—

1. In a tool of the character set forth, a 45 cutter-box having a series of radial slots therein, a spindle-box carried by said cutter-box, a series of cutter-bars in said cutter-box and having blades engaged in said slots, a screw-threaded spindle engaged in said 50 spindle-box and arranged to be rotated, and a cone on said spindle constructed when

moved downwardly by the action of the screw-threads on said spindle to force said cutter-bars and blades outwardly and at the completion of such downward movement to 55 engage said cutter-bars frictionally and rotate said cutter-box and blades.

2. In a tool of the character set forth, a cutter-box having a series of radial slots therein, a spindle-box carried by said cutter-box, an internal shoulder on said spindle-box, a series of cutter-bars in said cutter-box and having blades engaged in said slots, a screw-threaded spindle engaged in said spindle-box and arranged to be rotated, and 60 a cone on said spindle constructed when moved downwardly by the action of the screw-threads on said spindle to force said cutter-bars and blades outwardly and at the completion of such downward movement to 65 engage said cutter-bars frictionally and rotate said cutter-box and blades, and a collar on said spindle arranged to strike said shoulder and limit the upward movement of 70 said cone.

3. In a tool of the character set forth, a cutter-box having a series of radial slots therein, a spindle-box carried by said cutter-box, an internal shoulder on said spindle-box, a series of cutter-bars in said cutter-box and having blades engaged in said slots, a screw-threaded spindle engaged in said spindle-box and arranged to be rotated, a cone on said spindle constructed when moved downwardly by the action of the 80 screw-threads on said spindle to force said cutter-bars and blades outwardly and at the completion of such downward movement to 85 engage said cutter-bars frictionally and rotate said cutter-box and blades, a collar on 90 said spindle arranged to strike said shoulder and limit the upward movement of said cone, and means for adjusting said collar on said spindle relatively to said shoulder.

In testimony that I claim the invention 95 above set forth I affix my signature, in presence of two witnesses.

CHARLES C. MITCHEL.
